UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,377,211.

Specification of Letters Patent. Patented May 10, 1921.

Application filed October 4, 1919. Serial No. 328,484.

To all whom it may concern:

Be it known that I, RONALD A. McCANN, a citizen of the United States, residing at Swissvale, in the county of Allegheny and 5 State of Pennsylvania, have invented certain new and useful Improvements in Railway Signaling, of which the following is a specification.

My invention relates to railway signaling, 10 and particularly to signaling for stretches of single track over which traffic moves in both directions.

In signaling of this character, it is customary to provide a series of signals governing traffic in one direction, a line relay for each signal, each of which relays is normally controlled by the relay for the signal next in advance, and auxiliary relays for at times removing the line relays from such 20 control. One feature of my invention is the provision of novel and peculiarly effective circuits for the control of such auxiliary relays.

I will describe one form of signaling system embodying my invention, and will then point out the novel features thereof in 25 claims.

The accompanying drawings, Figures 1 and 2, when placed end to end in the order 30 named, constitute a diagrammatic view showing one form of signaling system embodying my invention.

Referring to the drawings, the reference characters 1 and 1^a designate the track rails 35 of a stretch of single track between two passing sidings L and M, and over which track traffic moves in both directions.

The stretch A—K between the two passing sidings is divided into a plurality of 40 sections by means of insulated joints 2, and each section is provided with a track circuit comprising as usual a track battery b and a track relay designated by the reference character T, with a suitable exponent.

45 As here shown, the track circuit for each section except for section C—D and F—G comprises a battery at one end of the section and a relay at the other end. In the case of sections C—D and F—G, however, 50 a track battery is located adjacent the middle of the section and the section is provided with two track relays located adjacent the ends of the section, respectively.

Traffic through the stretch from east to

west is governed by signals S', S³ and S⁵, 55 whereas traffic through the stretch from west to east is governed by signals S², S⁴ and S⁶. As here shown, each signal is located adjacent the junction of two track sections except the end signals S' and S², which 60 signals are located at the outer ends of the two end sections for the stretch.

Each signal is controlled by a line relay which is designated by the reference character R, with the same exponent as that used 65 for the corresponding signal. Each signal is provided with a circuit which is controlled by the corresponding line relay. Considering signal S³, for example, the control circuit is from a battery P³, through wires 3 and 4, contact 5 of relay R³, wire 6, operating mechanism of signal S³, wire 7, contact 8 of relay R³, and wires 9 and 10 to battery P³. Inasmuch as contacts 5 and 8 are closed 70 only when relay R³ is energized, it follows 75 that signal S³ will indicate stop when relay R³ is deenergized and proceed when this relay is energized. The controlling circuit for each signal is similar to the circuit just traced for signal S³.

The line relay for each signal (except as hereinafter noted) is normally controlled by the line relay for the signal next in advance governing traffic in the same direction, and by the track relays for all track 85 circuits lying between the two signals. Considering line relay R', for example, the controlling circuit for this relay is from battery P', through wires 3 and 11, contact 12 of relay R³, wires 13 and 14, contact 15 of 90 track relay T⁹, wire 16, contact 17 of track relay T¹⁰, wire 18, winding of relay R', common wire 0 and wire 10 to battery P'. Line relay R³ is similarly controlled by track relays T⁵, T⁶, T⁷ and T⁸, and by line 95 relay R⁵. Line relay R⁵, however, is controlled only by track relays T¹, T², T³ and T⁴, there being no line relay involved in the circuit for this relay. The control of the line relays for the signals governing traffic 100 from west to east is similar to the control of the line relays for signals S', S³ and S⁵.

Means are provided for at times removing line relay R' from control by line relay R³, this means being an auxiliary relay X³, 105 which is normally deenergized, but which when energized closes a shunt around contact 12 of relay R³. This shunt passes from

wire 3, through wire 19, contact 20 of relay X^3 and wire 21 to wire 14. Relay X^3 is provided with a pick-up circuit which passes from battery P^3 , through wire 3, contact 5 Q^3 operated by signal S^3 , wire 22, back contact 23 of track relay T^8 , wire 24, back contact 25 of relay T^9 , wires 26 and 27, winding of relay X^3 , wire 28, back contact 29 of relay R^3 , and wires 30 and 10 to battery 10 P^3 . Contact Q^3 is closed when signal S^3 indicates proceed, and open when this signal indicates stop. It will be seen, therefore, that relay X^3 can be picked up only when signal S^3 indicates proceed, relay R^3 15 is deenergized, and both track relays T^8 and T^9 are deenergized. Relay X^3 is provided with a holding circuit which passes from battery P^3 , through wires 3 and 31, contact 32 of relay X^3 , wires 33 and 27, winding 20 of relay X^3 , wire 28, back contact 29 of relay R^3 , and wires 30 and 10 to battery P^3 . This circuit is, of course, closed only when relay X^3 is energized and relay R^3 deenergized.

25 Signal S^5 is provided with a similar auxiliary relay X^5 , which, when energized, removes relay R^3 from control by relay R^5 . Signals S^4 and S^6 are provided with auxiliary relays X^4 and X^6 for similar purposes.

30 The operation of the system is as follows: Assuming first that a train passes through the stretch moving toward the west, it will be observed that as soon as such train passes 35 the point K, it will cause track relay T^{10} to open. This track relay opens at contact 17 the circuit for relay R' , so that signal S' moves to the stop position. Track relay T^{10} also opens the circuit for relay R^6 , so that signal S^6 moves to the stop position. Relay R^6 then opens the circuit for relay R^4 , and relay R^4 in turn opens the circuit for relay R^2 , so that signals S^4 and S^2 also move to the stop position. As the train passes out 40 of section H-K and into section G-H, track relay T^{10} becomes energized and track relay T^9 is opened, but this causes no change in the signal controlling circuits. As the train enters section F-G, it opens track relay T^8 , which in turn opens the circuit for line relay R^3 , so that signal S^3 starts to move toward the stop position. While the train is bridging the point G and before contact Q^3 opens, the pick-up circuit for auxiliary relay X^3 becomes closed. As soon as relay X^3 becomes energized, the stick circuit for this relay is closed and remains closed as long as line relay R^3 remains deenergized. When the rear of the train passes point G, 45 track relay T^9 closes so that relay R' again becomes energized and so causes signal S' to return to the proceed position. As the train proceeds through section F-G, it causes track relay T^7 to open and subsequently permits track relay T^8 to close, but

this causes no change in the controlling circuits for the signals. When the entire train has passed out of section F-G, track relay T^7 closes, but line relay R^6 remains open because its circuit is open at the lower contact 70 of relay X^3 . As the train passes through sections E-F and D-E, track relays T^6 and T^5 are opened successively, thereby holding relays R^3 and R^4 open and so holding signals S^3 and S^4 at stop. As the train passes 75 point D, signal S^5 moves to the stop position. Relay X^5 becomes energized by virtue of circuits which are similar to those for relay X^3 , so that after the rear of the train has passed point D relay R^3 becomes energized, whereupon signal S^3 returns to the proceed position. As soon as relay R^3 closes, the stick circuit for relay X^3 is opened, but the consequent opening of this latter has no effect on relay R' because the circuit for the latter relay is then closed at contact 12 of relay R^3 . The opening of relay X^3 , however, permits relay R^6 to close so that signal S^6 returns to the proceed position. When the rear of the train passes point A, signals S^2 , 90 S^4 , and S^5 returned to the proceed position. When relay R^5 closes, relay X^5 opens, thus again permitting relay R^3 to be energized through the front contact of relay R^5 . The parts of the system are thus restored to the 95 positions in which they are shown in the drawing.

The operation of the apparatus during the passage of a train from west to east will be understood from the foregoing explanation. 100 As soon as such train enters the section A-B, it causes signals S^2 , S^5 , S^3 and S' to assume the stop position. This movement of signal S^3 opens contact Q^3 , so that when the train subsequently bridges the point G, 105 the pick-up circuit for relay X^3 is not closed; in other words, relay X^3 becomes energized only when a train passes through the stretch moving toward the west.

The present invention is directed particularly to the pick-up circuit for each of the auxiliary relays X . One important feature of the invention is the provision of the back contact 29 (see relay X^3) of line relay R^3 in this pick-up circuit. This contact prevents relay X^3 from being energized unless relay R^3 opens, due to the entrance of a train into section F-G. In other words, if relay R^3 should stick in the closed position when a westbound train enters section F-G, relay 110 X^3 would remain open, so that signal S' would continue to indicate stop until the rear of the train has passed signal S^5 .

Another feature of the invention is the provision of the two back contacts 23 and 125 25 operated by track relays T^8 and T^9 , respectively, in the pick-up circuit for the auxiliary relay X^3 . Assuming that contact 25 of relay T^9 were omitted from this circuit, it will be evident that failure of track battery 130

6 for section F—G, which would permit track relay T⁸ to open, would cause relay R³ to open and so would cause relay X³ to close. An eastbound train entering the stretch 5 A—K would then fail to cause signal S' to assume the stop position. By controlling the pick-up circuit for relay X³ by both track relays T⁸ and T⁹, however, it will be seen that the simultaneous failure of two track 10 batteries would be necessary to cause false energization of relay X³, and the simultaneous failure of two batteries is, of course, not likely to occur.

Where in the accompanying claims I have 15 used the term "block," I mean the space between two adjacent signals governing traffic in the same direction, as, for example, the space between signals S' and S³, or between signals S³ and S⁵. Of these two blocks, the 20 block "G—K" is the "rear" and the block "D—G" is the "forward" block.

Although I have herein shown and described only one form of signaling system embodying my invention, it is understood 25 that various changes and modifications may be made therein within the scope of the appended claims without departing from the spirit and scope of my invention.

Having thus described my invention, 30 what I claim is:

1. In combination, a stretch of railway track, a plurality of signals located at intervals for governing traffic in one direction through said stretch, a line relay for each 35 signal, means for normally controlling each line relay by the line relay for the signal next in advance governing traffic in the same direction, track circuits for the stretch for controlling said line relays, an auxiliary relay for each line relay arranged when energized to remove such line relay from its 40 control of the line relay for the signal next in the rear, a pick-up circuit for each auxiliary relay including a back contact of the corresponding line relay, and a holding circuit for each auxiliary relay including said back contact of the corresponding line relay and a front contact of the auxiliary relay.

2. In combination, a stretch of railway 50 track, two signals governing traffic in one direction along said stretch, a line relay for each signal, means for normally controlling the line relay for the rear signal by the line relay for the forward signal, track circuits for said stretch for controlling said line relays, an auxiliary relay for the forward signal arranged when energized to remove the corresponding line relay from its control of the line relay for the rear signal, a pick- 55 up circuit for said auxiliary relay including a back contact of the corresponding line relay, and a holding circuit for said auxiliary relay including said back contact of the corresponding line relay and a front contact of the auxiliary relay.

3. In combination, a railway track divided into two blocks, track circuits for said blocks, a signal for each block, a line relay for the forward signal, means for controlling said line relay by the track circuits for 70 the forward block, means for normally controlling said rear signal by said line relay and by the track circuits for the rear block, an auxiliary relay for said forward signal arranged when energized to remove the rear 75 signal from control by said line relay, a pick-up circuit for said auxiliary relay including a back contact of said line relay, and a holding circuit for said auxiliary relay including said back contact of the corresponding line relay and a front contact of the auxiliary relay.

4. In combination, a railway track divided into two blocks, track circuits for said blocks, a signal for each block, a line relay 85 for the forward signal, means for controlling said line relay by the track circuits for the forward block, means for normally controlling said rear signal by said line relay and by the track circuits for the rear block, 90 an auxiliary relay for said forward signal arranged when energized to remove the rear signal from control by said line relay; a pick-up circuit for said auxiliary relay including a back contact of said line relay, a 95 back contact of the track relay for the forward track circuit of the rear block, and a back contact of the track relay for the rear track circuit of the forward block; and a holding circuit for said auxiliary relay including a front contact thereof and said back contact of said line relay.

5. In combination, a railway track divided into two blocks, track circuits for said blocks, a signal for each block, a line relay 105 for the forward signal, means for controlling said line relay by the track circuits for the forward block, means for normally controlling said rear signal by said line relay and by the track circuits for the rear block, 110 an auxiliary relay for said forward signal arranged when energized to remove the rear signal from control by said line relay, a pick-up circuit for said auxiliary relay including a back contact of said line relay and a contact operated by the forward signal and closed or open according as said signal indicates proceed or stop, and a holding circuit for said auxiliary relay including a front contact thereof.

6. In combination, a railway track divided into two blocks, track circuits for said blocks, a signal for each block, a line relay for the forward signal, means for controlling said line relay by the track circuits for 125 the forward block, means for normally controlling said rear signal by said line relay and by the track circuits for the rear block, an auxiliary relay for said forward signal arranged when energized to remove the rear 130

signal from control by said line relay; a pick-up circuit for said auxiliary relay including a back contact of said line relay, a back contact of the track relay for the forward track circuit of the rear block, a back contact of the track relay for the rear track circuit of the forward block and a contact operated by said forward signal and closed or open according as such signal indicates 10 proceed or stop; and a holding circuit for

said auxiliary relay including a front contact thereof and said back contact of said line relay.

In testimony whereof I affix my signature in presence of two witnesses.

RONALD A. McCANN.
